JOHN QUINCY REED, OF NEW YORK, N. Y., ASSIGNOR TO THE BUTTERICK
PUBLISHING COMPANY, (LIMITED,) OF SAME PLACE.

DESIGN FOR A LADY'S COSTUME.

Design No. 14,622, dated February 5, 1884.

UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 14,622, dated February 5, 1884.

Application filed December 26, 1883. Term of patent 33 years.

To all whom it may concern:

Be it known that I, JOHN QUINCY REED, of the city, county, and State of New York, have invented and produced a new and original 5 Design for a Pattern of a Lady's Costume, numbered 9,021; and I do hereby declare that the engraved prints accompanying this specification convey to any one accustomed to using paper patterns a clear understanding of how 10 to a garment made up by the pattern will appear.

The design shows a deep, round, closely-fitting basque, that exhibits a narrow vest between the fronts, a pocket-opening in each 15 front, narrow laps at the lower end of the center seam, coat-sleeves, and a rolling collar

with square ends, and a walking-skirt that displays a short pointed front drapery, exhibiting plaits in its back edges, and a full deep back drapery, exhibiting a different arrangement of plaits, and greater length at one side than at the other.

What I claim as my invention, and desire to secure by Letters Patent, is—

The design for a lady's costume, as shown 25 in the engraved prints accompanying this specification.

JOHN QUINCY REED.
